CUTTING AND ABRADING BLADE HOLDER

Laird F. Covey, Easton, Conn., assignor to The Stanley
Works, New Britain, Conn.

Filed Mar. 10, 1972, Ser. No. 233,849

Term of patent 14 years

Int. Cl. D8—05

U.S. Cl. D8—94

FIG. 1

FIG. 2

FIG. 3

FIG. 4

FIG. 5

FIG. 7

FIG. 6

FIG. 1 is a top view of the cutting and abrading blade holder of my new design;

FIG. 2 is a front view thereof;

FIG. 3 is a bottom view thereof;

FIG. 4 is a back view thereof;

FIG. 5 is a left end view thereof;

FIG. 6 is a right end view thereof; and

FIG. 7 is a sectional view taken along line 7—7 of FIG. 3.

The broken lines representing the blade are shown for illustrative purposes only and do not form a part of the claimed design.

I claim:

The ornamental design for a cutting and abrading blade holder, as shown and described.
